CLAIM

The ornamental design for a pipe connector, as shown and described.

DESCRIPTION

FIG. 1 is a front elevational view of a pipe connector showing our new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof;
FIG. 7 is a right side perspective view thereof;
FIG. 8 is a left side perspective view thereof;
FIG. 9 is another left side perspective view thereof;
FIG. 10 is a left side perspective view showing the pipe connector in a first use state;
FIG. 11 is a left side perspective view showing the pipe connector in a second use state;
FIG. 12 is a left side perspective view showing the pipe connector in a third use state;
FIG. 13 is a left side perspective view showing the pipe connector in a fourth use state; and,
FIG. 14 is a left side perspective view showing the pipe connector in a fifth use state.

In FIGS. 10–14 the drawings include broken lines that illustrate unclaimed environment in various states of use. The other broken lines depict portions of the pipe connector that form no part of the claimed design.
